Chas M. Candy Atty.

UNITED STATES PATENT OFFICE.

JOHN WICKS, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

ROTARY CONNECTER SWITCH.

Application filed June 30, 1922, Serial No. 571,947. Renewed April 22, 1925.

This invention relates in general to automatic switches for telephone systems, and the object of the invention is the provision of a new and improved rotary connecter switch.

More specifically, the object of the invention is to provide a rotary connecter switch having both directive and automatic primary or vertical movements, and having both directive and automatic secondary or rotary movements. The provision of a connecter having the foregoing characteristics, makes it possible to combine two or more levels into one large group, while at the same time another level may be divided into several small groups.

The means by which the foregoing objects are accomplished will be fully set forth hereinafter, reference being had to the accompanying drawings, of which Fig. 1 is a circuit diagram of the improved connecter, while Fig. 2 shows the wiring of the test contacts in certain levels of the connecter bank.

Referring to Fig. 1, the rotary connecter is indicated by the reference character H, and is of the well-known Strowger vertical and rotary type, having circuits such that it is controlled over the two sides of the incoming trunk in series. To the right of the connecter H are shown the bank terminals of a trunk line, which may extend to a private branch exchange and terminate in the jack J. It is to be understood that the trunk line shown is one of the group of similar trunk lines all extending to the same point.

In Fig. 2, the test contacts in the first four levels of the connecter have been shown. The test terminals are so connected that the four levels comprise one large group, three small groups and three individual lines. The large group consists of three sub-groups, the first sub-group consisting of the trunk terminals in the first level, the second sub-group consisting of the trunk terminals in the second level, and the third sub-group consisting of the first five trunk terminals in the third level. The first and second sub-groups as shown are equipped with chain relays, which as shown are connected to the bottom test terminals of their respective trunk lines. To the right of the bank terminals are shown the vertical test terminals, one for each level. When a trunk line is seized the chain relay associated therewith

energizes and completes at its working contact a portion of a circuit for placing a guarding potential on the vertical test terminal opposite the level in which the trunk line is located. When all the trunk lines in the first and second sub-groups are busy, all of the chain relays associated therewith will be energized, and circuits will be completed through the working contacts of the chain relays for placing guarding potentials on the vertical test terminals opposite such sub-groups. It will be noted that the last sub-group in the large group and the smaller groups have no means for placing a guarding potential on their respective vertical test terminals, as none is needed. The vertical test wiper is arranged to wipe over the vertical test terminals in its vertical movement, and to disengage therefrom on its rotary movement.

The apparatus, having been described more or less in general, will now be described in connection with the detailed description of its operation. For this purpose, it will be assumed that an automatic subscriber desires to obtain connection with a subscriber in the private branch exchange served by the large group of trunk lines. The customary subscriber's substation, individual line switch, and selector switches used by an automatic subscriber in completing a connection, being well understood by those skilled in the art and forming no part of the present invention, it is, therefore, believed that it will suffice to say that in response to the removal of the receiver by the calling subscriber, his individual line switch seizes an idle trunk line leading to an idle selector switch; and in response to the operation of the subscriber's calling device, the selector switch is operated to select an idle trunk line leading to another idle selector switch, or to select an idle trunk line leading to a connecter switch, such as indicated by the reference character H. Let us assume that the calling subscriber has established his connection up as far as the last selector, and that the selector has come to rest on its bank contacts, which are connected to the conductors 20, 21, and 22 of the connecter switch H, the connecter switch H being the first idle connecter accessible to said selector. When the selector switch comes to rest upon the contacts associated with conductors 20, 21, and 22, the switch-

ing relay of the selector completes an energizing circuit for the line relay 4 of the connector switch as follows: from ground by way of lower winding of line relay 4, normally closed springs controlled by the armature 31, conductor 21, over the intervening switches, and the subscriber's loop back to conductor 20, normally closed springs controlled by the armature 30, and through the upper winding of line relay 4 to battery. Relay 4, at armature 33 and its working contact, completes an energizing circuit for slow to release relay 5. Relay 5, upon energizing over the above traced circuit, connects ground to the release conductor 22 at armature 34 and its working contact, said ground completing a holding circuit for the switches back of the connector switch for maintaining said switches in an operated position, and, in addition, making the trunk line leading to connection H busy to all other selectors having access thereto; at armature 35 and its working contact prepares the circuit for the vertical magnet 15 and at its resting contact opens a point in the release circuit; and at armature 36 and its working contact prepares a locking circuit for relays 9 and 13.

The calling subscriber may now manipulate his calling device in accordance with the remaining digits in the number of the private branch exchange, which in this case are 1 and 1. Due to the operation of the calling device by the calling subscriber, the circuit of the line relay 4 is interrupted in a well-known manner and the line relay in response to this circuit interruption, deenergizes for a short interval and at this time a circuit may be traced for the vertical magnet 15 as follows: from ground by way of armature 33 and its resting contact, armature 35 and its working contact, normally closed off normal spring controlled by spring 68 and said spring, slow-acting relay 7, and vertical magnet 15 to battery. The vertical magnet 15 and relay 7 energizes in series, and by the operation of the vertical magnet 15, the switch shaft and wipers are raised until the wipers 70 to 73, inclusive, are opposite the first level and the vertical test wiper 95 in engagement with vertical test contact 78, which is opposite the first level. Relay 7, energizes and maintains its own circuit and that of the vertical magnet intact after the off normal springs have shifted, which they do on the first vertical step.

After the first impulse, the line relay 4 energizes and opens the circuit for relay 7 and vertical magnet 15 at armature 33. Relay 7, upon deenergizing, which it does after a short interval, switches the impulsing circuit from the vertical magnet to the rotary magnet at armature 40, and at armature 39 completes a testing circuit for vertical wiper relay 8.

If all the trunk lines in the first level are busy, there will be a ground potential on the vertical test contact 78 caused by the energization of the chain relays shown just below the first level (Fig. 2). Each chain relay, upon energizing, when its associated trunk line is seized, completes its portion of a chain of contacts by means of which ground is connected to the vertical test contact. Assuming that all the trunk lines in the first level are busy, the relay 7, upon deenergizing, completes an energizing circuit for the vertical wiper relay 8 as follows: from ground by the way of chain relay contacts, vertical test contact 78, vertical wiper 95, resting contact of armature 39 and said armature, and winding of relay 8 to battery. Relay 8, upon energizing, prepares a circuit for the vertical magnet 15 at armature 43 and its working contact, and at armature 41 and its working contact completes an energizing circuit for the stepping relay 6 as follows: from ground by the way of vertical test wiper 95, resting contact of armature 39 and said armature, interrupter spring 65 and its resting contact, working contact of armature 41 and said armature, and winding of stepping relay 6 to battery. Stepping relay 6 energizes and completes a locking circuit for itself as follows: from ground by way of working contact of armature 34 and said armature, working contact of armature 37 and said armature, armature 66 and its resting contact, working contact of armature 42 and said armature, resting contact of armature 39 and said armature, interrupter spring 65 and its resting contact of the vertical magnet, working contact of armature 41 and said armature, and winding of stepping relay 6 to battery. Relay 6 also completes a locking circuit for relay 8 from ground over a portion of the above traced circuit to armature 39 and thence through the winding of relay 8 to battery. Relay 6, in addition to completing a locking circuit for itself and relay 8, completes an energizing circuit for the vertical magnet 15 at armature 38 as follows: from ground by the way of working contact of armature 36 and said armature, armature 38 and its working contact, armature 43 and its working contact, and winding of vertical magnet 15 to battery. By the operation of the vertical magnet, the switch shaft and wipers are raised opposite the next or second level and the vertical test wiper comes into engagement with the vertical test contact 94 opposite the second level. The vertical magnet 15, at its interrupter spring 65, opens the locking circuit for relay 6, whereupon said relay deenergizes. Relay 6, upon deenergizing, opens the circuit for the vertical magnet at armature 38, and at armature 37 opens the locking circuit of the vertical wiper relay 8. The vertical magnet

deenergizes and closes its interrupter springs 65. The vertical wiper relay 8 deenergizes provided there is no ground potential on vertical test contact 94. If, however, all the 5 trunk lines in the second level are busy, there will be a ground potential on vertical test contact 94 and relay 8 will be maintained energized. The vertical magnet by closing its interrupter springs 65 then completes an energizing circuit for stepping relay 6. The stepping relay completes a locking circuit for itself and relay 8 and operates the vertical magnet. The vertical magnet again opens the circuit of the stepping 10 relay and this sequence of operations continues until the vertical test wiper no longer finds a ground potential or until it comes into engagement with a dead contact, whereupon the relays 6 and 8 and the vertical 15 magnet 15 are returned to their normal positions.

Returning now to just after the first automatic vertical step, and assuming that only the first three trunks in the second level are 20 busy, the vertical wiper relay 8 will deenergize due to there being no ground potential on the vertical contact 94 and the automatic vertical trunk hunting will stop. Relay 8, upon deenergizing, prepares the circuits for 25 the automatic rotary trunk hunting at armatures 41 and 43.

The subscriber may now dial the remaining or last digit of the called number or the digit 1. In response to the operation of 30 the calling device by the calling subscriber, the circuit of the line relay 4 is again interrupted. The line relay 4, upon deenergizing, completes a circuit for the rotary magnet 16 in series with relay 11 as follows: from ground by the way of armature 33 and its resting contact, armature 35 and its working contact, normally open off-normal springs controlled by spring 68, armature 40 and its resting contact, resting contact 35 of armature 49 and said armature, winding of relay 11, armature 59 and its resting contact, and winding of rotary magnet 16 to battery. The rotary magnet 16 and relay 11 energize in series. The rotary magnet 16 40 steps the wipers 70 to 73, inclusive, into engagement with the bank terminals of the first trunk in the second level, and moves the vertical test wiper 95 out of engagement with vertical test contact 94. Relay 11, upon energizing, at armature 53, and its working contact maintains the impulsing circuit for the rotary magnet closed, so that said impulsing circuit will not be opened at armature 49 when the wipers are passing 45 over busy trunks, at armature 51 and its resting contact opens the circuit to relay 6, so that said relay will not energize when wiper 71 is passing over busy trunks, and at armature 52 and its working contact, 50 completes an energizing circuit for relay 12. Relay 12, upon energizing, at armature 54 and its working contact prepares a circuit for relay 6, at armature 56 disconnects the busy machine, at armature 55 and its resting contact opens the circuit of the switching 55 relay 13, and at its working contact prepares the testing circuit for relay 10. As before stated, assuming the first three trunks in the second level to be busy, there will be a ground potential on the test terminals 60 which wiper 72 comes into engagement with or terminals 86, 87, 88, respectively; said ground extending from the connector switch occupying a multiple of that particular trunk line from a ground and armature similar to ground and armature 60 of the connector switch H. If the first trunk line in the second level is busy, ground from the lower private bank terminal 86 of said trunk line energizes test relay 10 by way of wiper 65 72, armature 55 and its working contact, armature 61 and its resting contact, and winding of relay 10 to battery. Relay 10, upon energizing, at armature 49 opens a point in the rotary impulsing circuit, at 70 armature 48 prepares a locking circuit for itself, and at armature 47 prepares a circuit for relay 6. A short interval after the rotary impulses have been sent, the series relay 11 deenergizes and at armature 52 opens 75 the circuit for the slow-acting relay 12. Relay 12, however, does not immediately deenergize and since the first trunk line in the second level is busy, a circuit for relay 6 may be traced as follows: from ground 80 potential on test terminal 86, over the conductor 90 connecting the bottom test terminal 86 with the top test terminal and from thence by way of test wiper 71, armature 54 and its working contact, armature 51 and its resting contact, armature 47 and its working contact, interrupter springs 66 of the rotary magnet, resting contact of armature 41 and said armature, and winding of relay 6 to battery. Relay 6, upon energizing, completes a locking circuit for itself 85 as follows: from ground on release conductor 22 by the way of working contact of armature 37 and said armature, interrupter springs 66 of the rotary magnet, resting contact of armature 41 and said armature, and winding of relay 6 to battery. Relay 6, in addition to completing a locking circuit for itself, closes a circuit for energizing the rotary magnet 16 and slow to release relay 12 in multiple as follows: from ground 90 by the way of working contact of armature 36 and said armature, armature 38 and its working contact, armature 43 and its resting contact, to junction point 96 where the circuit divides one branch going over the resting contact of armature 52 and said armature to relay 12, and the other branch extending from junction point 96 by way 95 of armature 59 and its resting contact, and 100

through the winding of rotary magnet 16 to battery. The above traced circuit for relay 12 maintains said relay in an operated position, it being remembered that relay 12 is slow to deenergize and, therefore, did not have time to fully deenergize before relay 6 was energized. The rotary magnet energizing over the above traced circuit, steps the wipers 70 to 73, inclusive, into engagement with the next or second set of bank terminals in the second level, and at its interrupter springs 66 opens the locking circuit for the stepping relay 6; whereupon said relay deenergizes. Relay 6, upon deenergizing, at armature 37 opens its own locking circuit and at armature 38 opens the circuit of the rotary magnet 16 and the slow to release relay 12. Before relay 12 has had time to deenergize, the testing circuit for relay 10 is again completed and if the trunk line is busy, relay 10 will be maintained energized from ground on test terminal 87 over a previously traced circuit, and a circuit may also be traced from ground at test terminal 87 for again energizing the stepping relay 6. Relay 6 again energizes and completes a locking circuit for itself as well as again completing the circuit for the rotary magnet and maintaining relay 12 in an operated position. The rotary magnet operates and steps the shaft wipers into engagement with the next set of bank contacts and in addition, opens the locking circuit of relay 6 at its interrupter springs 66. The relay 6, upon deenergizing, again opens the circuits for the rotary magnet 16 and the relay 12. Relay 10 again tests for a busy ground potential, and if the next trunk line is busy, the sequence of operations just explained continues until the wipers are rotated into engagement with an idle trunk line or the last trunk line in the level.

Assuming the fourth trunk line in the second level to be the first idle trunk line, the private wipers 71 and 72 will come to rest in engagement with the test terminals 75 and 76, respectively. As the test relay 10 no longer finds a ground potential on the test terminal 76 with which it is now in engagement, said relay deenergizes and prepares a circuit for the switching relay 13 at armature 48, and at armature 47 opens the circuit for the stepping relay 6 so said relay will not energize and operate the rotary magnet when this trunk line is made busy to other connector switches having access thereto, and at armature 50 opens a portion of the busy circuit. A short interval after relay 6 deenergizes, the slow-acting relay 12 deenergizes and completes a circuit for the switching relay 13 as follows: from grounded release conductor 22 by the way of armature 48 and its resting contact, upper winding of switching relay 13, resting contact of armature 55 and said armature, wiper 72, test terminal 76, and winding of chain relay 80 to battery. The switching relay 13 and the chain relay 80 energize in series. The chain relay 80, upon energizing, closes its contacts 84 and 85, thereby completing its portion of a chain of contacts for grounding the vertical test contact 94. The switching relay 13, upon energizing, closes at armature 58 a circuit through the low capacity condenser 97, whereby the calling subscriber is given the well-known ring-back tone when ringing current is applied to the called line, at armature 59 permanently opens the circuit for the rotary magnet, at armature 60 short circuits its upper winding, completes a holding circuit for chain relay 80, and places a ground potential on test terminal 76, thereby making the trunk line busy to other switches having access thereto; at armature 61 opens the circuit for the testing relay 10 so said relay cannot again energize, at armature 62 completes a locking circuit for itself from ground at armature 36, at armature 63 opens a point in the release circuit so as to prevent a premature release of the switch, and at armatures 57 and 64 connects ringing current to the trunk line, which current operates a visual signal at the operator's position in the private branch exchange. The circuit for ringing the visual signal or drop 81 at the private branch exchange may be traced as follows: By the operation of the interrupter relay 93 grounded generator and booster battery is intermittently placed on armature 69, and from thence the circuit may be traced through the upper winding of the ring-cut-off relay 9, resting contact of armature 44, and said armature, armature 57 and its working contact, wiper 70, line bank terminal 74, tip spring 82 of the jack J and its resting contact, condenser C, winding of drop 81, line bank terminal 77, wiper 73, working contact of armature 64 and said armature, and armature 46 and its resting contact to ground. The ring-cut-off relay 9 due to its construction, condenser C, and the high resistance of drop 81, will not energize over the above traced circuit, the drop 81, however, is operated over the above traced circuit to display to the operator at the private branch exchange a visual signal by means of which the operator is informed that a connection is desired. The operator, in response to the operation of the visual signal, inserts an answering plug of her cord circuit (not shown) into jack J, thereby disconnecting the drop 81 at spring 82 and its resting contact, and completing a circuit for the ring-cut-off relay as follows: from grounded generator or booster battery at armature 69, over the circuit previously traced to spring 82 and from thence through the operator's cord circuit back to spring 83 and ground at armature 46. Ring-cut-off relay 9, upon energizing, 130

completes a locking circuit for itself at armature 45 from ground at armature 36; and at armatures 44 and 46 disconnects ringing current from the called line and completes the talking circuit between the calling subscriber and the operator, and in addition, completes a circuit for the back bridge relay 3 as follows: from ground upper winding of said relay by way of working contact 5 of armature 44 and said armature, through the operator's cord circuit and back to the lower winding of said relay to battery. The back bridge relay, upon energizing, reverses the flow of current to the calling subscriber at armatures 30 and 31, and at armature 32 connects ground to conductor 98 so that the switch cannot release until the called subscriber hangs up. The operator, upon ascertaining the wants of the calling subscriber, completes the desired connection and conversation is carried on in the usual manner.

After conversation, the called party hangs up and relay 3 is deenergized, but the connection is held up by the calling subscriber. After a short interval, the calling subscriber hangs up and opens the circuit to the line relay 4, whereupon said relay deenergizes and opens the circuit to relay 5. After a short interval relay 5 deenergizes and removes ground from the release conductor 22, thereby allowing all the switches back of it to release and restore to normal; at armature 36, relay 5 opens the holding circuit for relays 9 and 13, allowing said relays to release, and at armature 35 completes a circuit for the release magnet 14 to allow the switch to return to normal. The release magnet 14 is energized over the following path: from ground at armature 33 and its resting contact, armature 35 and its resting contact, armature 63 and its resting contact, off normal spring 67 and its working contact, and release magnet 14 to battery. The release magnet is maintained energized over the above traced circuit until the shaft and wipers are returned to their normal position, whereupon the circuit of the release magnet is opened when the off normal springs are operated, which they do when the switch reaches its normal position.

Should, however, the calling subscriber be the first to hang up after conversation, the following operation takes place. Relay 4 deenergizes and in turn opens the circuit for relay 5. Relay 5, however, being slow-acting, retains its armature attracted for a short interval at which time a circuit may be traced for relay 12 as follows: from ground by the way of armature 33 and its resting contact, armature 35 and its working contact, normally open off normal springs controlled by the spring 68, armature 40 and its resting contact, resting contact of armature 49 and said armature, winding of relay 11, resting contact of armature

52 and said armature, and winding of relay 12 to battery. Relay 11 does not energize in series with relay 12, the latter relay, however, energizes and removes ground at armature 60 by way of upper winding of relay 13 and armature 55 from the release conductor 22, so that when relay 5 is fully deenergized the switches back of the connector switch H will release. After an interval, relay 12 falls back and again grounds the release conductor by way of armature 55 through the upper winding of relay 13, thereby making the switch busy until the called subscriber hangs up. When the called subscriber hangs up, relay 3 releases and opens the locking circuit for the relays 9 and 13 and said relays release and return the switch to normal in the usual manner.

Having described the operation of the switch in connection with establishing a connection with the private branch exchange, a brief description will now be given how the calling subscriber receives the busy signal when all the trunks to the private branch exchange are busy.

The subscriber dials the first digit or digit 1 of the called number, and the vertical magnet is operated to step the shaft and wipers up to the first level. With all the trunk lines busy, there will be a ground potential on the vertical test contacts 78 and 94 and the vertical magnet will automatically operate as previously explained, to step the shaft and wipers up to the third level. In response to the second digit of the call number, the rotary movement of the switch is started. The first five trunk lines in the third level being busy, the wipers are automatically rotated into engagement with the fifth set of contacts in the third level. As will be noted in Fig. 2, the two test terminals 91 and 92 are not strapped together and said switch will stop with its wipers 71 and 72 in engagement with said test terminals, as a circuit is no longer completed for the stepping relay 6. Ground, however, on test terminal 92 maintains the testing relay 10 energized and said relay is locked up from the grounded release conductor 22 when relay 12 deenergizes. When relay 12 is fully deenergized the busy tone is transmitted to the calling subscriber through armatures 56 and 50 in the well-known manner, whereupon the calling subscriber hangs up and releases the switch as previously described.

It will also be noted that the last test terminals in the first and second levels are not strapped. The reason for this is that, should there be but one idle trunk in one of the levels, say the second level, and two connector switches such as H should start rotating nearly simultaneously to seize said idle trunk line, one of the connector switches would reach the idle trunk line before the other and make it busy to said other con-

necter switch. The other connector switch would continue to rotate until it reached the last test terminal in the second level, where it would stop and transmit to the calling subscriber a busy signal as previously described.

A brief explanation will now be given of how the connector switch establishes connection with a trunk in a small group, such as the group shown in Fig. 2, comprising the

10 last five trunk terminals in the third level.

The digits necessary to call this group are the digits 3 and 6, and in response to the subscriber dialling the first digit or digit 3, the switch raises its shaft and wipers opposite the third level. In response to the dialling of the last digit or digit 6, the switch rotates its wipers into engagement with the sixth set of contacts in the third level. If this trunk line is busy, the wipers are automatically rotated to find an idle trunk line in the same manner as previously described. It will be noted that in the selection of small groups of trunk lines, the vertical test wiper has no function, as the vertical test contacts 20 associated with such groups are left dead.

The connector switch is also capable of completing connections with a private or individual line, the test terminals of three of such individual lines being shown as the last 30 three sets in the fourth level in Fig. 2. Connections to these lines, however, are directly controlled by the calling subscriber. The desired line is not tested until the wipers have been rotated into engagement with the 35 bank terminals of the desired line, whereupon the desired connection is completed if the line is idle, or if the line is busy, the busy tone is given the calling subscriber in the well-known manner.

40 Having fully described and ascertained the features of my invention, what is considered to be new and desired to have protected by Letters Patent, will be pointed out in the appended claims.

45 I claim:—

1. In a telephone system, a two wire side switchless connector, lines divided into groups and sub-groups accessible to said connector, means for directly controlling the operation of said connector in a primary movement to select a group, means for continuing the primary movement to automatically select a sub-group in the selected group, directly controlled means 50 for operating said connector in a secondary movement, and means for automatically continuing the secondary movement to select an idle line in the selected sub-group.

2. In a telephone system, a two wire side 60 switchless connector, lines divided into groups and sub-groups accessible to said connector, a primary motor magnet for operating said connector in a primary movement to select a group in accordance with a digit of the called number, means for continuing the primary movement to automatically select a sub-group in the selected group, directly controlled means for operating said connector in a secondary movement, and means for automatically continuing the secondary movement to select an idle line in the selected sub-group.

65

tinuing the primary movement to automatically select a sub-group in the selected group, a secondary motor magnet for operating said connector in a secondary movement in accordance with another digit of the called number, and means for automatically continuing the secondary movement to select an idle line in the selected sub-group.

3. In a telephone system, a connector, 75 lines divided into groups and sub-groups accessible to said connector, means for directly controlling the operation of said connector in a primary movement to select a group, a stepping relay for continuing the primary movement to automatically select a sub-group in the selected group, directly controlled means for operating said connector in a secondary movement, and circuit connections for operating said stepping relay to automatically continue the secondary movement to select an idle line in the selected sub-group.

4. In a telephone system, a connector, 80 lines divided into groups and sub-groups accessible to said connector, a primary motor magnet for operating said connector in a primary movement to select a group in accordance with a digit of the called number, a stepping relay for controlling further operation of said primary motor magnet to cause said magnet to automatically continue the primary movement to select a sub-group in the selected group, a secondary motor magnet for operating said connector in a secondary movement in accordance with another digit of the called number, and circuit connections for operating said stepping relay to control the operation of said secondary motor magnet to automatically continue the secondary movement to select an idle line in the selected sub-group.

5. In a telephone system, a connector, 85 lines divided into groups and sub-groups accessible to said connector, means including a magnet for directly operating said connector in a primary movement to select a group, a stepping relay having a circuit including contacts operated by said magnet, means including said magnet and relay for automatically causing the connector to select another group in case the group first selected is busy, means for then directly operating said connector in a secondary movement to select a line in the selected group, and means for causing the connector to automatically select another line in case the line first selected is busy.

6. In a telephone system, a vertical and 125 rotary connector, lines divided into groups and sub-groups accessible to said connector, means for directly operating said connector in a vertical movement to select a group, means for continuing the vertical 130

movement to automatically select a sub-group in the selected group, directively controlled means for operating said connector in a rotary movement to select a line in the 5 selected sub-group, means for automatically continuing the rotary movement in case the selected line is busy, a stepping relay included in the means for continuing the vertical movement, and another relay for 10 switching the said stepping relay into association with the rotary operating mechanism when the vertical movement is completed.

7. The combination, with an automatic 15 switch having two successive directive

movements and two hunting movements, of groups of trunk terminals any one of which groups may be selected on the first directive movement, the second directive movement being effective to select a particular 20 terminal in any selected group, means dependent on the idle condition of the selected group and terminal for cancelling either or both hunting movements, and groups of chain relays for indicating the conditions of 25 said groups to said switch.

In witness whereof, I hereunto subscribe my name this 28th day of June, A. D., 1922.

JOHN WICKS.
